FOREIGN PATENT DOCUMENTS

EP 0138513 B1 2/1988
WO 2013151737 A1 10/2013*Primary Examiner* — Angela J Lee*Assistant Examiner* — Shawn T Gingrich(74) *Attorney, Agent, or Firm* — Barnes & Thornburg LLP(57) **CLAIM**

We claim, the ornamental design for a circuit breaker, as shown and described.

DESCRIPTION

FIG. 1 is a perspective view of a circuit breaker, as shown in an exemplary embodiment;

FIG. 2 is a front view of the embodiment of FIG. 1;

FIG. 3 is a rear view of the embodiment of FIG. 1;

FIG. 4 is a side view of the embodiment of FIG. 1;

FIG. 5 is another side view of the embodiment of FIG. 1;

FIG. 6 is a top view of the embodiment of FIG. 1; and,

FIG. 7 is a bottom view of the embodiment of FIG. 1.

The broken lines shown in the Figures are environmental and not part of the claimed design.
